UNITED STATES PATENT OFFICE

JAMES F. HARDY, OF NEW YORK, N. Y.

DESIGN FOR A SEWING-MACHINE FRAME.

SPECIFICATION forming part of Design No. 24,710, dated September 24, 1895.

Application filed August 26, 1895. Serial No. 560,606. Term of patent 14 years.

To all whom it may concern:

Be it known that I, JAMES F. HARDY, of the city and county of New York, in the State of New York, have invented and produced a new and original Design for a Frame for Sewing-Machines, of which the following is a specification.

The essential features of my design consist in a frame for sewing-machines in which the base and overhanging arm extend substantially at right angles to the standard, the three parts—base, standard, and overhanging arm—forming, when viewed from the side, three sides of a rectangle, the standard, when viewed from the end, presenting rounded cheeks upon opposite sides near the base, and the base, when viewed from above, presenting rounded cheeks upon its opposite sides intermediate of its ends.

In the accompanying drawings, Figure 1 is a view of the frame in side elevation. Fig.

2 is a view in end elevation, and Fig. 3 is a top plan view.

The base is denoted by A and the rounded cheeks upon its opposite sides by *a*.

The standard is denoted by B and the rounded cheeks on its opposite sides by *b*.

The overhanging arm is denoted by C and terminates at its free end in a vertically-elongated head *c*, provided with flanges *c'*, extending at right angles thereto at its upper and lower ends.

The base has a hollow web *a'* projecting upwardly from it.

What I claim is—

The design for a sewing machine frame, as shown and described.

JAMES F. HARDY.
